UNITED STATES PATENT OFFICE.

GUSTAVUS MILLHISER, OF RICHMOND, VIRGINIA, ASSIGNOR TO THE MILLHISER MANUFACTURING COMPANY, OF SAME PLACE.

DESIGN FOR A TOBACCO-PACKAGE.

SPECIFICATION forming part of Design No. 29,192, dated August 9, 1898.

Application filed July 13, 1898. Serial No. 685,872. Term of patent 14 years.

To all whom it may concern:

Be it known that I, GUSTAVUS MILLHISER, a citizen of the United States, residing at Richmond, in the county of Henrico and State of Virginia, have invented a certain new and useful Design for Cloth Tobacco-Packages, of which the following is a specification, reference being had therein to the accompanying drawings, in which—

Figure 1 is a perspective view; Fig. 2, a side elevation, and Fig. 3 a plan view.

My design consists of a cloth or textile package having a circular flat base *a* and a circular substantially flat top *b*, the edge *c* of the package being continuous and circular and standing at right angles to the upper and lower faces. On the upper face are formed a series of radiating plaits or folds *d*, which ex-

tend from near the center of the package to the edge in the manner of a rosette. In the center of the upper side is an opening *e*, from which radiate the plaits or folds. Over the opening is a bow-knot of cord or twine *f*. The package is the same vertical thickness throughout, the upper and lower faces being substantially parallel.

I claim—

The design for a tobacco-package substantially as herein shown and described.

Signed by me, at Washington, District of Columbia, this 11th day of July, 1898.

GUSTAVUS MILLHISER.
